CLAIM

The ornamental design for a hair comb, as shown and described.

DESCRIPTION

FIG. 1 is a front perspective view of a hair comb, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion of the hair comb shown within the area designated as 9 in FIG. 2; and, FIG. 10 is enlarged view of a portion of the hair comb shown within the area designated as 10 in FIG. 5.

The broken lines in the drawings illustrate the portions of the hair comb, which form no part of the claimed design.

The dash-dot-dash broken lines encircling portions of the hair comb in FIGS. 2 and 5 and illustrated in the enlarged views in FIGS. 9 and 10 form no part of the claimed design.
